UNITED STATES PATENT OFFICE.

SVERRE RACHSTANG SVENDSGAARD, OF PORTLAND, OREGON.

TOILET OUTFIT.

1,426,021.

Specification of Letters Patent. Patented Aug. 15, 1922.

Application filed October 4, 1921. Serial No. 505,416.

To all whom it may concern:

Be it known that I, SVERRE R. SVENDSGAARD, a citizen of the United States, and a resident of Portland, in the county of Multnomah and State of Oregon, have invented certain new and useful Improvements in Toilet Outfits, of which the following is a specification.

The present invention relates to a portable toilet or lavatory outfit or equipment especially adapted for use on automobiles.

The object of the invention is to provide an article of this character which provides motorists with the facilities necessary to enable them to thoroughly cleanse or wash the hands or otherwise satisfactorily prepare the toilet after changing tires or performing repair work while on the road; which is highly organized so as to be of simple and durable construction, compact form, attractive appearance and susceptible of convenient and cheap manufacture and of ready association with the standard types of motor vehicles.

Other objects and advantages of the invention reside in certain novel features of construction, combination and arrangement of parts which will be hereinafter more fully described and particularly pointed out in the appended claims, reference being had to the accompanying drawings forming part of this specification, and in which:

Figure 1 is a view in front elevation of the preferred embodiment of the invention, parts being broken away and shown in section for the sake of illustration;

Figure 2 is a view thereof in end elevation, parts being broken away and shown in section for the sake of illustration; and

Figure 3 is a detail view in section of the non-spilling cap construction utilized in conjunction with both filling necks.

Referring to the drawings wherein for the sake of illustration is shown the preferred embodiment of the invention, the numeral 10 designates generally the main or water receptacle. The water receptacle may be of any suitable design but preferably is constructed with front and rear walls 11 and 12, respectively, and a curved bottom wall 13 which extends between the front and rear walls and which is extended upwardly at each side to provide the side walls 14 and 15. A top wall, designated generally at 16 is associated with the front and rear and the side walls and includes sections 17 and

18 having double functions as will presently appear. A water gage for the water receptacle is provided and preferably comprises a transparent panel 19 inset in the front wall 11 and suitably packed to prevent leakage. A faucet or spigot 20 is connected with water receptacles at the lower central point of a bevel portion 21 which connects the front wall and the bottom and side walls, as shown in Figures 1 and 2. In this manner the spigot constitutes a valve controlled outlet for all of the water of the receptacle. Brackets, comprising apertured attaching ears 22, are carried by the main water receptacle and facilitate the mounting of the device on a suitable support on the automobile or the like.

A towel receptacle, indicated at 25, surrounds the water receptacle and includes a front wall 26, a rear wall 27 and side walls 28 and 29. The front and rear walls 26 and 27 and the side wall 28 are respectively coplaner and preferably integral with the front and rear walls 11 and 12 and the side wall 14 of the water receptacle 10 but the side wall 29 comprises a distinct wall which upstands from the line of juncture of the sections 17 and 18 of the top wall 16 of the water receptacle. The section 17 of the top wall 16 thus also serves as the bottom wall of the towel compartment while the section 18 provides a readily accessible shelf as will hereinafter appear, a hinged top 30 completing the towel receptacle. The towel compartment is adapted to contain a supply of paper towels which may be in the form of folded sheets but which preferably consists of a roll of absorbent tissue 31 mounted on a shaft 32 having trunnions 33 rotatably journaled in bearings provided therefor in the side walls of the towel receptacle.

A soap container, designated generally at 35 is provided and includes a cylinder 36 arranged within the water receptacle and depending from the section or shelf 18 of the top wall 16. The lower end of the cylinder 36 is closed by a head 38 which rests on a bracket 39 to aid in the support of the cylinder. An outlet pipe 40 leads laterally from the lower end of the cylinder through the front wall 11 of the water receptacle, suitable packing being provided between the outlet pipe and the front wall to prevent leakage, and carries at its outer end a faucet or spigot. The upper end of the cylinder

36 communicates with a filling cap 42 located on the shelf 18. A similar filling cap 43 is also located on the shelf in spaced relation to the filling cap 42 and provides a means whereby the water receptacle may be filled.

The filling caps 42 and 43 are of identical construction so that a common description will serve for both. As shown in Figure 3 10 each includes a filling neck 45 exteriorly threaded and provided at its upper end with an upstanding annular flange 46 and with a circumferential series of V-shaped notches 47 adjacent said flange. A sealing disk 48 15 extends across the open end of the filling neck to close or seal the same and is mounted on a flanged carrier 49 having V-shaped lugs 50 received in the V-shaped slots of the neck. A cap 51 is interiorly threaded and engaged 20 with the exteriorly threaded filling neck and has its top provided with an air vent 52. A compression coil spring 53 is arranged in the cap 51 and bears against the carrier 49 to force the sealing disk into packing or 25 sealing engagement with the filling neck.

It is obvious that the soap container may be placed on the outside of the receptacle as well as on the inside thereof, as has been previously described.

30 I claim:

1. A toilet outfit or the like comprising a water receptacle having front and rear walls, a curved bottom wall extended upwardly to provide side walls and a top wall including 35 sections, a faucet connected with the front wall immediately above the lowermost point of the bottom wall, a towel receptacle arranged on one of the sections of the top wall of the water receptacle having a rotatable 40 roller therein adapted to carry a roll of towel tissue, and a hinged top, the other section of the top of the water receptacle comprising a readily accessible shelf, a soap container arranged within the water receptacle and comprising a cylinder depending 45 from the shelf and having its lower end closed, a bracket supporting the closed end, a filling cap arranged on the shelf and communicating with the cylinder, an outlet pipe leading laterally from the lower end of the cylinder through and exteriorly of the water receptacle, a faucet connected with the outer 50 end of the outlet pipe, and a filling cap for the water receptacle arranged on said shelf in spaced relation to said first mentioned filling cap.

2. A toilet outfit or the like comprising a water receptacle having a top including sections, a faucet constituting the outlet of said 60 water receptacle, a towel receptacle arranged

on one of the sections of the top of the water receptacle, the other of said sections providing a readily accessible shelf, a soap container arranged within the water receptacle adjacent said shelf, an outlet pipe leading 65 from the soap container through and exteriorly of the water receptacle, a faucet connected to the outer end of the outlet pipe, a filling cap arranged on said shelf and connected with the soap container, and a filling 70 cap for the water receptacle arranged on said shelf in spaced relation to the first mentioned filling cap.

3. A toilet outfit or the like comprising a water receptacle having a top, a faucet constituting the outlet of said water receptacle, 75 said water receptacle having a readily accessible shelf, a soap container arranged within the water receptacle adjacent said shelf, an outlet pipe leading from the soap 80 container through and exteriorly of the water receptacle, a faucet connected to the outer end of the outlet pipe, a filling cap arranged on said shelf, and connected with the soap-container, and a filling cap for the 85 water receptacle arranged on said shelf in spaced relation to the first mentioned filling cap.

4. A toilet outfit including a water receptacle and a soap container arranged in said 90 water receptacle and comprising a cylinder having its lower end closed, an outlet pipe leading laterally from said cylinder through and exteriorly of said water receptacle, a faucet connected to the outer end of said 95 outlet pipe and a filling cap for said soap container arranged exteriorly of said casing.

5. A toilet outfit or the like comprising a water receptacle having a top including two sections, a towel receptacle mounted on one 100 of said sections, the other of said sections of said top constituting a readily accessible shelf, a soap container arranged in the water receptacle, a filling cap for the soap container arranged on said shelf and a filling 105 cap for the water receptacle positioned on said shelf in spaced relation to said first mentioned filling cap.

6. A toilet outfit or the like comprising a water receptacle having a readily accessible 110 shelf, a soap container arranged within said water receptacle, a filling cap for the soap container arranged on the shelf and a filling cap for the water receptacle arranged on said shelf in spaced relation to the first mentioned cap, each of said caps including a filling neck, a cap connected thereto and spring pressed means between the cap and the filling neck for preventing leakage.

SVERRE RACHSTANG SVENDSGAARD.
